SHAMPOO APPARATUS

Nettie M. Howe, Austin, Minn.

Application February 8, 1938, Serial No. 189,468

4 Claims. (Cl. 4—159)

This invention relates to improvements in apparatus for use by hair dressers and pertains particularly to an apparatus for use in shampooing the hair.

5 The present invention has for its principal object to provide an improved structure for facilitating the process of shampooing the hair, wherein novel means is provided to enable the shampooer or hairdresser to work freely and to flood 10 the hair freely with water when necessary without danger of any of the water or shampoo material flowing down over the face or down the neck of the person receiving the shampoo.

15 Another object of the invention is to provide a novel shampoo apparatus in which novel means is employed for protecting the person receiving the shampoo and for collecting and carrying off the shampoo water and rinse water without making it necessary for the person receiving the 20 treatment to move from the position originally assumed.

A still further object of the invention is to provide in an apparatus of the above described character, a novel means for forming a fluid tight 25 contact between a sink or tray-like portion of the apparatus and the head of the shampooee below the hair line of the latter, whereby the complete shampooing process may be carried out without having to disturb the person receiving the 30 treatment.

The invention will be best understood from a consideration of the following detailed description taken in connection with the accompanying drawing forming part of this specification, with 35 the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a view in side elevation of the improved apparatus embodying the present invention, portions of the same being in section and illustrating the position occupied by a person receiving the shampoo.

Figure 2 is a view in top plan of the drain tray. Referring now more particularly to the drawing, the numeral 1 generally designates a base for the apparatus embodying the present invention and while any suitable mechanism may be employed for supporting the upper or working part of the apparatus, there is here illustrated a 55 lower standard in the form of a tubular member

2, the lower end of which is secured by a set screw 3 in a collar 4, which forms an integral part of the base 1.

Slidably extended into the upper end of the tubular portion 2 of the standard is an upper shiftable standard 5, this part 5 with the part 2 constituting the complete supporting structure for a tray unit, which is indicated as a whole by the numeral 6. The upper part of the supporting structure, that is the rod 5, has its lower end slideable into the tubular part 2 and is surrounded by the collar 6' which normally rests upon the upper end of the portion 2 and has a set screw 7 which may be threaded inwardly for binding contact with the rod 5 so that by resting upon the upper end of the portion 2, this collar will sustain the rod 5 in any desirable vertically adjusted position.

The numeral 8 generally designates a tray through the center of which is a sleeve 9, through 20 which the rod 5 passes, this tray resting upon the collar 6' and serving as a receptacle for soap or other materials.

Adjacent its upper end, the rod 5 has secured thereto the supporting arm or arms 10 on which 25 towels or other articles may be suspended and above these arms the rod is provided with a transverse slot 11 which is formed on one side to provide the lip 12.

The upper end of the rod 5 is suitably reduced, 30 as at 13, to form a pivotal connection with a pair of ear members, one only of which is shown and is indicated by the numeral 14. These ear members are integral with and extend downwardly from the underside or bottom 15 of the tray 6 35 and are pivotally coupled with the part 13 of the standard 5 by a suitable thumb nut and screw assembly 16, by means of which oscillatory adjustment of the tray 6 upon the upper end of the supporting standard or rod 5 is facilitated.

The tray 6 is preferably of the elongated rectangular contour illustrated in Figure 2 and it will be noted that the hinge connection between the upper end of the rod 5 and the bottom of the tray which is formed by the parts 13 and 14 is adjacent one end of the tray.

The tray 6 has the bottom 15, previously referred to, and the upstanding forward edge and side edge flanges 18 and 19 respectively, and the side flanges merge at the rear of the tray into the 50 side walls of a hood 20, which extends across the tray to form a waste water receiving basin which has an outlet nozzle 21 adjacent the rear end of and extending through the bottom 15. The nozzle 21 has coupled therewith, when the device is 55

in operation, a suitable waste water carry-off tube 22 which may lead to a suitable drain.

Upon the top of the hood of the waste water receiving basin, there is secured by means of 5 the bracket 23, the pipe elbow coupling 24 into one side of which is secured one end of a pipe 25 which is adapted to have a suitable water supply hose 26 attached thereto, while the vertically directed portion of the coupling 24 has 10 connected therewith the upwardly extending pipe 27 which is attached, through the medium of the universal coupling 28, to one end of the forwardly and downwardly curving tubular arm 29. It is preferred that a portion of this tubular arm 15 be of flexible character, as indicated at 30, and to the free end of this portion 30 there is attached the spray head 31 which preferably has the concave spray face 32, so that water issuing therefrom instead of being spread out into a 20 "rose," will be more or less concentrated toward a central area.

The bottom 15 of the tray 6 is provided with an opening 33 toward the center of which the spray head 31 is directed. This opening has the 25 upwardly and outwardly turned edge flange 34 which extends throughout the circumferential extent of the opening, as is shown in Figure 2.

The numeral 35 designates a flat rubber diaphragm having a central opening 36 which is 30 rolled to form a reinforcing bead, as illustrated, while the peripheral edge of the diaphragm is provided with the inturned bead 37. This in-turned bead of the outer edge of the diaphragm is designed for engagement under the upturned, 35 flange 34 of the opening 33 so that the diaphragm will be stretched across the opening with the opening 36 of the diaphragm co-axial with the opening 33 of the tray.

When the apparatus is to be used, the person 40 who is to receive the shampoo projects his head up through the opening 36 of the diaphragm so that the beaded edge of the opening may be positioned around the head in tight contact therewith below the hair line. Thus, the entire 45 hair covered portion of the head will be above the diaphragm 35, as illustrated in Figure 1, and due to the relatively tight contact between the edge of the opening 36 and the head, no water 50 can flow down over the face or down the neck of the person who is to receive the hair treatment.

The tray 6 is adjusted to the desired inclination to suit the person receiving the shampoo and is maintained in such position through the 55 provision of the arcuate rack 38, one end of which is pivotally attached to the underside of the tray 6 as indicated at 39. This pivotal connection is located between the pivot 46 and the aperture 33 and the free end of the rack is 60 extended through the opening 11 of the standard 5, so that when the end of the tray 6 nearest the aperture 33 is raised or lowered, the rack will move accordingly through the opening 11 and the teeth 40, which are formed upon the convex 65 edge of the rack, will have sliding engagement with and over the lip 12. It will thus be readily apparent that when the desired adjustment of the tray 6 has been made, one of the teeth 40 will engage the lip 12 and will maintain the tray in 70 the adjusted position.

It will be readily obvious that with the construction shown, the necessary adjustments for height and for the proper tilt of the tray 6 may

be easily and quickly made to suit the individual who is to receive the hair treatment and it will also be obvious that as the hair is treated and washed, the shampoo solution and the rinse water will flow down across the diaphragm to 5 the bottom of the tray and to the rear thereof into the catch basin provided from whence the liquid will flow off through the tube 22.

I claim:

1. A shampoo apparatus comprising a tray 10 having a bottom provided with a head receiving opening adjacent one end, means for carrying off liquid from the tray, means supporting the tray in a manner facilitating its adjustment at a desired inclination from the horizontal, an up- 15 wardly and outwardly extending flange carried by the tray and defining said head receiving opening, and a head engaging resilient dia- phragm in the form of a flat annulus having its peripheral edge formed for resilient detachable 20 engagement under said flange whereby the central open portion of the annulus may receive and engage a head extended through the opening, beneath the hair line thereof.

2. A shampoo apparatus comprising a tray 25 having a bottom provided with a head receiving opening adjacent one end, means for carrying off liquid from the tray, means supporting the tray in a manner facilitating its adjustment at a de- 30 sired inclination from the horizontal, an up- wardly and outwardly extending flange carried by the tray and defining said head receiving opening, a head engaging resilient diaphragm in the form of a flat annulus having its peripheral edge formed for resilient detachable engagement 35 under said flange whereby the central open portion of the annulus may receive and engage a head extended through the opening, beneath the hair line thereof, and a spray fixture carried 40 by the tray and having a spray nozzle adapted to be directed downwardly toward said opening.

3. A shampoo apparatus comprising a tray, 45 means for connecting a water lead-off tube to the tray, the tray having a head receiving opening through its bottom, an upwardly and out- wardly turned flange integral with the tray bot- 50 tom and surrounding said opening, means for establishing a water tight connection between a head extended into the opening and the flange of the opening comprising a flat rubber annulus 55 having a peripheral turned back edge formed to be stretched over said flange, the inner edge of said annulus being formed for tight contact with the head adjacent the hair line, and means carried by the tray for projecting fluid down- 60 wardly upon a head in said opening.

4. A shampoo apparatus, comprising a tray having a bottom provided with a head receiving opening, a flange encircling said opening upon the upper side of said bottom to lie within the 65 tray and curving upwardly and laterally from the opening, and a head engaging resilient dia- phragm in the form of an annulus having a portion of the periphery turned under to form an encircling inturned rib, the said rib of the 70 annulus being engageable under said flange by stretching the annulus over said opening and the central portion of the annulus being designed to receive and engage about the head whereby a water-tight connection is established between the head and the tray.

NETTIE M. HOWE.
